VENDING MACHINE

Ernest W. Handley, Arlington, and Walter G. Segerstrom, Somerville, Mass., assignors to Trimount Coin Machine Company, Boston, Mass., a corporation of Massachusetts

Application January 26, 1939, Serial No. 252,918

4 Claims. (Cl. 312—67)

The present invention relates to vending machines and in particular to vending machines in which packaged articles are vended, and more particularly packaged articles of uniform size and shape such as sticks of gum or small bars of confection or other small uniform packages which are flat and may be stacked one upon another in the vending machine.

In the present invention the articles are stacked or packed in columns in such a manner that they occupy a small space so that a comparatively large quantity of packages may be stored in the machine and therefore avoid refilling at frequent intervals.

In the present machine this is accomplished without substantially using more space by arranging the columns in rows for which one outlet serves for ejecting the packages. In combination with this the coin inserted in the machine serves as a connecting element for releasing a lock mechanism so that the machine may be operated for ejecting the packages from one or the other column in which the packages are stacked. The packages are taken from the columns alternately by movement of a member which reciprocates back and forth ejecting the lowest package in the column in the outlet of the machine.

Other and further advantages will be understood from the following specification containing a description of an embodiment of the present invention together with the drawings, in which:

Figure 1 is a side elevation of a portion of the vending machine indicating the invention.

Figure 2 is a fragmentary front elevation of the machine shown in Figure 1.

Figure 3 is another front elevation of the machine shown in Figure 1 but with the front cover plate removed.

Figure 4 is a sectional view taken on the line A—A of Figure 5, and,

Figure 5 is a plan view of the machine shown in Figure 1.

Referring specifically to the drawings, the vending machine, it will be noted contains two frames 6 in which there are stacks of the articles to be vended, designated 1 and 2 respectively in Figure 4. These articles may be gum, chocolate, or any uniform package that may be uniformly stacked so that the machine may operate to advance the articles all in the same way. The frames supporting the articles comprise end and back supports 3 and 4 respectively extending as high as it is desired to make the vending ma-

chine, the end supports 3 having angles 15 extending from the ends as shown in Figure 5. The side supports 3 of the frames may be fixed to the side plates 5, by the brackets 5' by welding or otherwise, which plates 5 are a part of the frame of the machine. This side plate 5 also supports the mechanism shown in Figure 1 for advancing the position of the articles being vended and also the mechanism of the coin selector system cooperating with the first named mechanism for vending the merchandise.

The frames 6 are partially closed at the bottom by the bracket members 7 extending at right angles from the sides of the frames 6, but the center section of the frame is open at the base to allow the reciprocating mechanism to operate to eject the packages as will be presently described. For this purpose an opening 8 is left at the bottom of the wall 4 of the frame sufficiently large so that only one package may be ejected at a time. At the base of the frames is a platform or plate 9 with an opening 10 positioned between the frames into which the package is sent upon leaving the frame. This ejection from the frame 6 through the opening 10 is accomplished by means of the ejector 11 which comprises a flat plate 12 with a large center opening 16 as wide as the package to be vended is long, upon which is mounted at the end portions two flat square cornered C shaped members 13 and 14 positioned back to back. The sides of the center opening 16 are provided with upwardly extending walls 17 about the same height as the C shaped members. The inner edges of the C shaped members are positioned far enough apart so that when the inner edge of one member has just passed beyond the side wall of the frame, the inner edge of the other member is beyond the further side wall of the other frame. The top sides of the C shaped members must however be sufficiently long so that when they pass to an inside position between the frames, these top elements still support the columns of packages and prevent the lowest package from resting upon the base of the frame until the C shaped member returns to its position external of the wall 15 when the column will drop and a new package will be in position to be vended. The walls 3 and 15 extend all the way down to the base bracket 7, so that the packages may not be pushed outward from the center line position as viewed in Figure 4.

The ejector plate 11 is reciprocated back and forth in the manner about to be explained and first ejects from one column 1, for instance, as

the element 14 moves to the center and then from the column 2 as the element 13 moves to the center, in each case through the opening 16 in the plate 11 and into the opening 10 which sends the package down a chute not shown, and out of the machine. In the ejector plate 11 beneath the member 14 is a rectangular slot 18 (Figure 5) through which there projects an arm 19 (Figures 5 and 4) which extends upwardly from the bell crank lever 20 pivoted to the base 21. The bell crank lever 20 is provided with a recess 22 by means of which the cam is engaged by the cylinder 23 which is mounted eccentrically in its face plate 24 to the spur gear 25 by means of the bolt 26.

The spur gear 25 is shown in face view in Figures 3 and 2, and comprises symmetrically placed teeth 27 with deeper recessed portions 28 and 29, each portion having at its border on one side, a slight flange 30, extending from the plane of the gear itself. This flange (Figure 1) in the normal inoperative position, bears against the projection 32 of the cam 33 which is pivoted to the upright plate 5 on the pivot 34. The cam 33 is also provided with a projecting finger 35 to which is fastened a helical spring 36, the other end of which is mounted to the frame 5 through the bracket 38 held to the frame by the screw 37. The cam is therefore tensioned against the projection 32 by means of the spring 36 and while it will move with the downward movement of the projection 32, it will fly back to the position indicated in Figure 1 and engage the second projection 32 at the edge of the other recess as the rotation of the spur gear brings this recess into position before the projection.

The cam 33 works in conjunction with the bar 39 and the coin 40 in the manner which will presently be described. The bar 39 is mounted externally of a side plate 41 which is rigidly attached to the plate 5 by means of the screws 42 as indicated in Figure 1. This side plate 41 has a portion 43 pressed outward from the rest of the plate forming a narrow pocket 44 (Figure 2) in which the coin 40 finally drops after being deposited, but before being freed and sent into the coin box below the plate from the outlet 45. The bar 39 slides with respect to the side plate 41 between two sets of guides 46, 46, pressed out from the side plate 41 at the top of the bar 39 and 47, 47 positioned at the bottom of the bar 39. The side plate 41 is provided with an opening 48 along a portion of the bar 39, and the bar in turn has a projecting arm 49 projecting into this opening and into the narrow pocket 44.

The cam 33 also swings or rotates in this narrow pocket, but is positioned away from the arm 49 of the bar 39 so that no contact will be established between the two unless the correct coin is deposited in the position shown in Figure 1. The coin gains the positions indicated in the figure by passing through the slot 50 between the edge of the side plate 41 and the back plate 5 and dropping down until its lower edge rests on the wall edge 51 formed by the plates 41 and the plate 5. It should also be noted that the bar 39 has a flange 52 at its forward end projecting into the same recess 28 or 29 as the arm 32 of the cam 33, and that it is tensioned in this position by the spring 53, one end of which is hung onto the bar 39 as indicated at 54 and the other end of which is hooked to the prong 55 fastened to the plate 5.

With no coin in position when the spur gear 25 is rotated, the side of the gear comes down 75

upon the projecting arm 52 of the end of the bar 39 and the gear is locked and the mechanism will not operate to work the ejector plate 11. When however the correct coin is in position as indicated in Figure 1 in dotted lines, the initial depression of the arm 32 of the cam 33 sends the other portion of the cam 33 near the coin 40 to the right as shown in Figure 1 and moves the coin into contact with the edge of the arm 49 of the bar 39. The bar 39 is therefore moved to the right as shown positioned in Figure 1 and to such an extent that when the edge 30 of the spur gear 25 comes into the position of the end 52 of the bar 39, the bar 39 has moved sufficiently to the right that the gear will clear the bar and rotation of the spur gear will continue. The motion of the cam 33 is completed after the portion 30 of the spur gear has passed beyond the arm 32 whereupon the end of the arm 32 will bear upon the back of the spur gear 25 and be ready to snap into the next recess as it comes into position.

The action of the cam 33 during this operation has also been to push the coin 40 to the right 25 in Figure 1 and along the wall 60 into the opening 45 from where the coin goes to the coin pocket. When the coin has left the space between the cam 33 and the arm 49, the bar 39 again becomes disengaged and the spring 53 forces the bar to the left, with the result that the end of the cam 52 comes up against the back of the spur gear 25 ready to drop into the recess in the spur gear.

The purpose of the teeth of the spur gear is 35 simply to prevent rotation of the handle 61 in the direction opposite to that intended. To accomplish this, there is mounted on the face plate 62 in which the shaft 63 is journaled, which shaft carries the spur gear 25 and the cylinder 23, a 40 spring tensioned cam 64, having a projecting pawl 65 engaging the gear 25 to prevent motion in the direction of the arrow 66.

When the handle is turned in the right direction as permitted by the freeing of the spur gear 45 by the coin, the rotation of the eccentrically positioned cylinder 23, working in the recess 22 of the bell crank lever 20, swings the cam in a counter-clockwise direction as viewed in Figure 5 and the arm 19 of the cam working in the slot 18 of the ejector plate 11 carries the plate backwards or to the right as shown in Figures 4 and 5, thus permitting the C shaped element 14 to eject the lowest package 70 from the column 1. It will be noted that an arcuate slot 71 is provided in the plate 9 so as to permit the free motion of the cam arm 19. The continued rotation of the bell crank lever 20 brings the plate 11 over to the right in Figures 4 and 5, to the point where the package 70 is deposited into the opening 10, and further motion commences the return of the plate whereupon the element 13 begins the ejection of the package which has dropped down in the frame to the base and which now is in the path of the element 13.

For this purpose however two coins will be necessary because for each half turn the spur gear is locked by the end 52 of the bar 39.

The mechanism for selecting the coins does not form a part of the present invention and any well known means may be used, provided the coins are fed to the place herein indicated and are of the dimensions to allow proper operation of the machine.

The mechanism of the present invention may be incorporated in many types and styles of ma-

chines, but principally provided as will be noted from the description above, front and rear columns and therefore may contain double the merchandise contained in a single column machine.

Having now described our invention, we claim:

1. In combination in a vending machine for vending flat packages, means for supporting a plurality of vertical columns of the packages to be vended in rows with a space between the columns slightly larger than that of the packages to be vended, said columns supporting means having at their bases, openings adjacent said space, means positioned to engage said openings for ejecting the packages from the bases of said columns comprising a member having its end portions raised the thickness of said packages to engage said openings at the bases of said columns, said end portions being spaced from each other at their nearest edges the distance of the space between the columns plus the width of one of said columns, means manually rotatable, and means adapted to be operated by said manually rotatable means for reciprocating said ejecting means and ejecting said packages alternately from the base of each of said columns into the space therebetween, said space being covered by a wall having an opening therein through which the ejected articles pass when moved into said space.

2. In combination in a vending machine, means manually rotatable for delivering articles to be vended, means rotatable eccentrically therewith, a bell crank lever pivoted in a plane perpendicular to the plane of rotation of said first means and having one end operable by said eccentric means, a frame having means for supporting in columns articles to be vended, with an opening between said columns through which the ejected articles pass, ejecting means in operative relation to said columns at the base thereof, said ejecting means being connected to the other end of said bell crank lever and operative in a plane perpendicular to said manually rotatable means, said ejecting means also adapted to be reciprocated back and forth in relation to said columns with the continued rotation of said rotating

means for ejecting the articles through said opening.

3. In combination in a vending machine, means operable manually for ejecting therefrom articles to be vended comprising a rotatable shaft having an open ended cylindrical cam mounted eccentrically on said shaft, a bell crank lever pivoted with its axis of rotation normal to the shaft and having a recess on one side on its periphery engaging the open end of said cylinder and on the other side an arm having a projecting member, a frame having means for supporting in columns articles to be vended, with an opening between said columns through which the ejected articles pass, ejecting means in operative relation to said columns at the base thereof, said ejecting means having a slot engaging the projecting member of said lever whereby said ejecting means is adapted to be reciprocated back and forth in relation to said columns for ejecting the articles through said opening.

4. In combination in a vending machine, means operable manually for ejecting therefrom articles to be vended comprising a rotatable shaft having an open ended cylindrical cam mounted eccentrically on said shaft, a bell crank lever pivoted with its axis of rotation normal to the shaft and having a recess on one side on its periphery engaging the open end of said cylinder and on the other side an arm having a projecting member, a frame having means for supporting in columns articles to be vended, with an opening between said columns through which the ejected articles pass, ejecting means in operative relation to said columns at the base thereof, said ejecting means comprising a tray with an open center freely supported for horizontal motion across the base of said columns and having upwardly projecting portions for sliding the articles out from the base of the columns into said open center and a slot at one end of the tray engaging the projecting member of said lever whereby said ejecting means is adapted to be reciprocated back and forth in relation to said columns for ejecting the articles through said opening.

ERNEST W. HANDLEY.
